UNITED STATES PATENT OFFICE.

HUGH P. McMILLAN, OF BALTIMORE, MARYLAND, ASSIGNOR TO SAMUEL M. DELL & CO. INC., OF BALTIMORE, MARYLAND, A CORPORATION OF MARYLAND.

BRUSH.

Application filed March 16, 1923. Serial No. 625,594.

This invention relates to improvements in brushes and is particularly directed to that class of brushes wherein the bunch of bristles contains a wedge to expand the same into engagement with a surrounding metal ferrule or band.

The present invention especially resides in the means for securing the bunch of bristles to the handle.

10 The invention is illustrated in the accompanying drawing, wherein:—

Fig. 1. shows the brush in side elevation.

Fig. 2. illustrates the same in vertical cross-section.

15 Fig. 3. shows a top or plan view of the metal bound bunch of bristles, the handle being omitted, and

Fig. 4. illustrates an inverted or bottom view of the detached handle.

20 Fig. 5. shows a form of fastening in perspective.

Referring to the drawing the numeral 5, designates the bristles of the brush which are arranged in a bunch and are encircled by a 25 metal ferrule 6 which latter has the shape the brush is to assume.

30 Into the butt-ends of the bunch of bristles, I drive two wedges 7 which latter are spaced apart in that they are arranged on opposite sides of a central line passing through the bunch of bristles. This arrangement provides a central filling of bristles 8 between the outer sides of the wedges and the ferrule.

35 During the formation of the bunch of bristles I preferably, but not necessarily, place a central tube 10 in the central filling 8 of bristles between the two wedges which tube extends preferably from the upper to the 40 lower edges of the wedges, as seen in Fig. 2 of the drawing.

It will be noted by reference to Fig. 3 of the drawing that bristles are provided all around the central tube 10 so that the only 45 cavity between the wedges is at the center of the brush and that this central cavity is only the diameter of the tube.

The metal ferrule or band 6 is so placed 50 on the bunch of bristles as to project slightly above the root ends thereof and thereby form a cavity or socket on top of the bunch. Into this cavity or socket the lower end of the handle is to be placed, as will presently be described.

55 The handle 11, in this instance, is flat on

two sides and has a flange portion 12 at its base. This flange portion is of a width and depth to snugly fit into the socket over the butt-ends of the bristles, and when so placed, the handle will practically seat on the upper 60 surfaces of the two spaced-apart wedges and over the upper end of the central tube 10.

After the handle is in place the bristles of the bunch are spread open at the center and a fastening 13, carrying a lateral projection or a head 14, is passed up through the tube 10 and entered in the bottom of the handle until the lateral projection or head 14 seats against the under side of the tube and also preferably against the bottom 70 edges of the two spaced-apart wedges as clearly shown in Fig. 2, and the handle is thereby secured directly to the bunch of bristles.

By preference, I form the head 14 of the 75 fastening in such a way as to provide an upwardly-extending projection 17, whose shape will vary according to the shape of the head and the character of the fastening device.

The upwardly-extending projection 17 of 80 whatever form it may be will be embedded in the two spaced-apart wedges whereby it will serve to hold the two wedges from bulging laterally at opposite sides of the central tube 10 or the hole through which the fastening 85 passes in case the tube is omitted.

For purposes of finish, I usually place a leather band 15, around the outer side of the ferrule and drive tacks 16 through the latter and also through the ferrule 6 into the 90 flange 12 of the handle.

I may also provide a series of nails 18 through the leather band 15 and bristles into the wedges.

Having described my invention, I claim:— 95

1. In a flat brush the combination with a bunch of bristles, of a band around the butt-ends thereof, two spaced apart parallel disconnected wedges in the butt-ends of the bunch, a wooden handle above the wedges 100 and a fastening extending up between the two parallel wedges and into the handle said fastening having a head which extends across the space between and engages the under sides of the parallel wedges said head 105 having means to prevent the wedges from spreading apart.

2. In a brush the combination with a bunch of bristles, of a band around the butt-ends thereof, two spaced apart wedges in the 110

butt-ends of the bunch, a handle above the wedges and a fastening extending up between the two wedges and into the handle said fastening having a head of a size to extend across the space between the wedges and said head having upwardly-extending projecting means thereon which latter enter the material of the wedges and hold the same from spreading apart.

10 3. In a brush the combination with a bunch of bristles, of a band around the butt-ends thereof, two spaced apart wedges in

the butt-ends of the bunch, a handle above the wedges and a fastening extending up between the two wedges and into the handle said fastening having a T-shaped head to extend across the space between the wedges and each arm of the head having a projection thereon to enter the wedge above it whereby the two wedges will be held from spreading apart.

In testimony whereof I affix my signature.

HUGH P. McMILLAN.
